UNITED STATES PATENT OFFICE.

DON N. THOMPSON, OF SYRACUSE, NEW YORK, ASSIGNOR TO PASS & SEYMOUR, INC.,
OF SOLVAY, NEW YORK, A CORPORATION OF NEW YORK.

ELECTRIC SWITCH.

Application filed July 25, 1918. Serial No. 246,710.

To all whom it may concern:

Be it known that I, DON N. THOMPSON, a citizen of the United States, and residing at Syracuse, Onondaga County, State of New York, have invented certain new and useful Improvements in Electric Switches, of which the following is a specification.

This invention relates to electric switches of the quick make and break type and it is especially useful as a push button switch to be used in connection with electric lighting circuits.

The invention is illustrated in the accompanying drawings, in which:

Figure 1 is a plan view of a switch embodying the invention;

Figure 2 is a central section on the line 2-2 of Figure 1 parts being shown in side elevation;

Figure 3 is a plan view of the switch shown in Figure 1 separated from the base and showing the circuit through the switch closed;

Figure 4 is a side view of the switch with the parts in the same relation as in Figure 3;

Figure 5 is a section on the line 5-5 of Figure 1;

Figures 6, 7 and 8 are perspective views of parts of the switch mechanism;

Figure 9 is a sectional side view of another form of switch embodying the invention;

Figure 10 is a plan view of the same looking upward from approximately the line 10-10, of Figure 9;

Figure 11 is a sectional view on the line 11-11 of Figure 9;

Figure 12 is a plan view of a slightly different type of switch embodying the invention;

Figure 13 is a sectional view on the line 13-13 of Figure 12;

Figure 14 is a side view of the switch shown in Figure 12;

Figures 15 and 16 are details of the switches shown in Figures 9 and 12 respectively.

Referring particularly to Figures 1 to 8 inclusive, 20 indicates an insulating base of porcelain or other suitable material, 21 the wire terminals, and 22 switch terminals which are to be connected electrically by means of the switch. The switch mechanism comprises a rocking plate 23 which may be termed a switch plate and which carries

switch arms 24 adapted to cooperate with the switch terminals 22. Beneath the plate 23 is centrally located with respect to said plate is a fulcrum plate 25 which is maintained in proper relation with the plate 23 by reason of wings 26 which enter slots 27. The fulcrum plate 25 has lugs 28 at its ends which engage notches 29 on the upturned arms of the base plate 30 to prevent the switch plate from moving longitudinally beyond the proper bounds. The fulcrum plate or bar 25 extends down from the switch plate at right angles thereto, as clearly shown in Figures 2 and 4, and this fulcrum plate always rests on the base plate, the notches 29 being so deep that the lugs 28 do not rest on the bottom thereof. The switch plate is thrown from the position shown in Figure 2 to the position shown in Figure 4, and vice versa, by the following means.

A bar 31 carrying push buttons 32 also carries a spring operated plunger 33 which continuously presses on the switch plate 23. The plunger 33 is guided in an opening in the bar 31 and in an opening in a bracket 34 which is carried by the bar 31 in parallel relation thereto, as shown in Figures 2 and 5. The plunger 33 has shoulders near its lower end and it is continually pressed down against the switch plate by a spring 35 which is interposed between the bracket 34 and these shoulders. It will be seen that as the push buttons are moved one way or the other the plunger 33 must move with them horizontally. If the buttons and the bar 31 are moved to the right from the position shown in Figure 2, the plunger will ride up on the switch plate 23, compressing the spring 35 which brings more and more pressure to bear on the switch plate until the plunger has passed the vertical plane through the contact between the fulcrum plate and the base plate. After passing this plane the plunger will tip the switch plate 23, for instance, from the position shown in Figure 2 to the position shown in Figure 4 and the switch will close, as shown in Figure 4. A reverse movement of the push buttons causes the reverse or opening movement of the switch arms.

There is a tendency in the switch plate 23 to resist the rocking movement due to the friction of the fulcrum plate 25 on the plate. When this frictional contact ceases to hold the switch instantly rocks from one extreme to the other thus making or breaking con-

tact quickly. The switch always rests on the fulcrum plate and one edge of the switch plate, both of which bear on the base plate, as shown in Figures 2 and 4 and hence it is perfectly stable in either position. In throwing the switch from one extreme to the other it remains in its initial position as heretofore described until the plunger passes the center of the switch plate 23 when the switch shifts with an instantaneous or snap action. The operation of the switch is superior to switches of a somewhat similar type in which the switch plate swings on trunnions or pivots for the reason that the frictional engagement of the fulcrum plate 25 with the base breaks suddenly and permits the switch to move from one extreme position to the other instantaneously. As illustrated in the drawings, the bar 31 connecting the push buttons is guided by pins 36 which are mounted in lugs 37 extending upward on opposite sides of the base plate 30. The spring 35 continuously presses the bar 31 against the pins 36.

In Figures 9, 10, 11 and 15, the switch operating device, substantially as heretofore described, is shown for operating a switch of a slightly different type. Referring to these figures, 40 indicates a switch plate for connecting the terminals 41. This switch plate is mounted on the end of the fulcrum bar 25. In order to insulate the plate 40 from the bar, it has connected to it a plate 42 of insulating material which is slotted centrally to receive the bar as shown in Figures 9 and 11. The base plate 23 of this switch is rocked by a spring plunger 33 in the manner above described when the push buttons 32 are operated. The switch arms 34 shown in Figures 1 to 5 are of course omitted in Figures 9 to 11 and are substituted by the switch member 40. In other respects the switch shown in Figures 9 to 11 does not differ materially from the switch shown in Figures 1 to 5. Figure 15 shows a keyhole opening 29a in which the fulcrum plate 25 has a limited movement.

In Figures 12, 13, 14 and 16 is shown another form of the invention in which a rocking plate 50 carries switch arms 51 which cooperate with circuit terminals 52. In this type of switch the fulcrum plate is substituted by a right angled or V section fulcrum 53 which is attached to the fulcrum plate by having its edges crimped over the same, as shown at 54. The rocking or switch plate 50 is guided in circular openings 55 in the side flanges of a base plate 56. The push buttons 57 are connected to a bar 58 which slides on this base plate and the switch plate 50 is rocked by a spring tongue 59, which is carried by the bar 58, the side arms of the spring tongue 58 being coiled about lugs 60 on the push bar 58, the free ends of these wire arms being passed

through lugs 61 on the bar as clearly shown in Figures 12 and 14.

In operation the spring tongue 59 travels with the push buttons and their connecting bar. When, for instance, the buttons are moved to the left from the position shown in Figure 13, the spring moves over the inclined switch plate 50, its tension increasing without moving the switch plate or switch arms until the contact point of the spring approaches the left edge of the plate 50. The switch then immediately snaps over from the position shown in Figure 13 to the position shown in Figure 14. It will be noted that in Figure 13 one face of the V shaped plate 53 rests on the base plate while in Figure 14 the other rests on the base plate. In all of the forms of the switches illustrated there is no dead center on which the switch is inclined to hold or drag. The movement from one extreme position to the other in all forms is practically instantaneous. It will be evident that the principle involved in this switch can be applied in various ways to different electrical devices and it is to be understood that the several forms shown in the drawings are simply illustrative of some of these applications.

Having thus described the invention what is claimed as new and desired to be secured by Letters Patent is:

1. In an electric switch, the combination with a stationary base plate, of a switch plate, a fulcrum centrally arranged beneath the switch plate and rigidly connected thereto, said fulcrum resting on the base plate, a spring operated device movable across the switch plate from one side of said fulcrum to the other and vice versa, means for restraining bodily movement of the switch plate along the base plate, and a switch member connected to the switch plate.

2. In an electric switch, a switch operating device comprising a stationary base plate, a switch plate adapted to rock with respect to the base plate, a fulcrum plate rigidly connected with the switch plate and extending at right angles thereto and arranged between the switch plate and base plate, and spring means travelling on the switch plate adapted to rock the same.

3. In an electric switch, the combination with a base plate, of a push bar movable parallel with the base plate, a switch plate arranged between the push bar and the base plate, a fulcrum device centrally connected with the switch plate and resting on the base plate and a spring plunger carried by the push bar and movable therewith in contact with the switch plate from side to side of the fulcrum, whereby the switch plate is caused to shift with a snap action.

4. In an electric switch, the combination with a stationary base plate, of a rocking switch plate, a fulcrum device movable with

the switch plate and resting on the base plate and movable relatively thereto, and a spring device movable over the switch plate to shift the same, the base plate serving to limit the 5 movement of the switch plate in either direction.

5. In an electric switch, the combination with a base plate having upturned notched arms, a switch plate between said arms, a 10 fulcrum plate connected with the switch plate and having lugs engaging the said notches, the fulcrum plate resting on the base plate, and a spring device movable across the switch plate to rock the same, the 15 movement of the switch plate being limited in both directions by contact of its respective edges with the base plate.

6. In an electric switch, the combination with a base plate having upturned notched 20 arms, a switch plate between said arms, a fulcrum plate connected with the switch plate having lugs engaging the said notches, the fulcrum plate resting on the base plate, and a spring device movable across the 25 switch plate to rock the same, the movement of the switch plate being limited in both directions by contact of its respective edges with the base plate, and a push bar arranged to move at right angles to the switch plate, 30 said spring device being mounted in the push bar.

7. In an electric switch, the combination with a stationary member, of a switch plate spaced therefrom carrying contact points, 35 means for pivotally supporting said switch plate at its central portion from said stationary member including a fulcrum plate secured in position across said switch plate and bearing at its opposite edge on the surface of said fixed member, a movable spring 40 pressed member having a contact end bearing on said switch plate pressing it towards said fixed member, and means for causing said spring pressed member to move along 45 said switch plate from one side of its pivot line of turning at said fulcrum plate to the other to cause tilting in one direction or the other and consequent slight frictional sliding movement of said fulcrum plate on said 50 fixed member.

8. In an electric switch, the combination with a stationary member, of a switch plate spaced therefrom carrying contact points, 55 means for pivotally supporting said switch plate at its central portion from said stationary member including a fulcrum plate secured in position across said switch plate and bearing at its opposite edge on the surface of said fixed member, a movable spring 60 pressed member having a contact end bearing on said switch plate pressing it towards said fixed member, and means for causing said spring pressed member to move along said switch plate from one side of its pivot 65 line of turning at said fulcrum plate to the

other to cause tilting in one direction or the other and consequent slight frictional sliding movement of said fulcrum plate on said fixed member, and means for so limiting the tilting movement that the spring pressed 70 point will remain in contact and may then be moved reversely on it.

9. In an electric switch, the combination with a stationary member, of a switch plate carrying contact points, means for maintaining the central portion of said switch plate in a substantially fixed position in reference to and a material distance from the stationary member while permitting its ends to tilt or turn with its central portion as the 75 pivot line including a fulcrum plate secured to said switch plate and making contact with said fixed member in a plane at right angles to and across the central portion of said switch plate, a movable operating member having secured thereto and movable therewith a spring pressed member having a point bearing against the surface of said switch member on the side opposite said stationary member, and means for so moving 80 said operating member as to cause said spring pressed point to pass along said switch plate from one side of its center tilting or turning line to the opposite side, thereby causing a sudden change of position 85 of said switch plate through a tilting or turning movement when the spring pressed point has passed beyond the fulcrum or point of turning a sufficient distance to overbalance the frictional resistance caused by 90 the contact of said fulcrum member with said fixed member.

10. In an electric switch, the combination with a stationary base plate having thereon a pair of upwardly extending marginal lugs near each end, cross pins connecting each pair of lugs near their upper ends, a push bar longitudinally movable between said lugs of each pair and adapted to bear against the under surface of said pins, 105 an upwardly extending bracket on said push bar between said pair of lugs having an opening vertically aligned with a hole through said push bar, a plunger vertically slidable in said openings provided with an 110 upwardly facing shoulder, a coil spring on said plunger bearing upwardly on said bracket and downwardly on said shoulder and a rocking switch plate between said 115 push bar and base plate against the upper surface of which said plunger bears.

11. In an electric switch, the combination with a stationary base plate having thereon a pair of upwardly extending marginal lugs near each end, cross pins connecting 120 each pair of lugs near their upper ends, a push bar longitudinally movable between said lugs of each pair and adapted to bear against the under surface of said pins, an 125 upwardly extending bracket on said push bar 130

- bar between said pair of lugs having an opening vertically aligned with a hole through said push bar, a plunger vertically slidable in said openings provided with an upwardly facing shoulder, a coil spring on said plunger bearing upwardly on said bracket and downwardly on said shoulder, a switch plate midway between said pairs of lugs and between said push plate and 10 base on the upper surface of which said plunger bears, contact arms extending upwardly from said switch plate on opposite sides of said push bar and a fulcrum support for said switch plate resting on said 15 base.
12. In an electric switch the combination with a stationary base plate, a switch plate extending along said base plate having upwardly extending centrally arranged contact 20 tact arms on opposite sides, a fulcrum support interposed between said switch plate and base plate in midway position, a longitudinally movable push bar above said switch plate between said arms and a spring 25 pressed plunger carried by said push bar in midway position projecting at its lower end through said push bar and pressing on the upper surface of said switch plate.
13. In an electric switch the combination 30 with a stationary base plate, a switch plate extending along said base plate having up-
- wardly extending centrally arranged contact arms on opposite sides, a fulcrum support interposed between said switch plate and base plate in midway position, having only contact connection with said base plate and switch plate, a longitudinally movable push bar above said switch plate between said arms and a yielding plunger carried by said push plate pressing downward at its lower end on the upper surface of said switch plate.
14. In an electric switch the combination with a stationary base plate, a switch plate extending along said base plate having upwardly extending centrally arranged contact 50 arms on opposite sides, a fulcrum support interposed between said switch plate and base plate in midway position, having only contact connection with said base plate and switch plate, a longitudinally movable push bar above said switch plate between said arms and a yielding plunger carried by said push plate pressing downward at its lower end on the upper surface of said switch plate.

In testimony whereof I affix my signature.

DON N. THOMPSON.
